UNITED STATES PATENT OFFICE.

LEONARD S. BALUTA AND GEORGE A. McAFFEE, OF BERWICK, PENNSYLVANIA.

CLOTHESPIN.

Application filed June 7, 1923. Serial No. 643,965.

To all whom it may concern:

Be it known that we, LEONARD S. BALUTA and GEORGE A. McAFFEE, citizens of the United States, residing at Berwick, county 5 of Columbia, and State of Pennsylvania, have invented certain new and useful Improvements in Clothespins, of which the following is a specification.

This invention relates to clothes pins, and 10 the primary object of the invention is to provide a clothes pin of novel construction which is reinforced in a novel manner to make it break-proof at a point where most of the strain is put upon the ordinary one-piece pin, causing it to split and rendering 15 it useless.

When the ordinary one-piece clothes pin is employed in securing clothes to the line there is always a liability of the pin breaking 20 either under the strain of a relatively thick object or the action of wind against the clothes, causing the clothes either to fall off of the line to the ground, often soiling or ruining them, or to be carried away 25 by the wind. It is true that these pins are manufactured to sell at a relatively low cost, but the value of a pin which will overcome these objectionable features without adding much to the cost of manufacture will be 30 apparent.

Another object of this invention is to provide a pin having its article gripping portion formed in a novel manner to prevent slipping off of the line.

A still further object is to provide a pin 35 which is strong and durable in construction, one which will have a maximum of utility, and one which will be cheap to manufacture.

Other objects of the invention will be apparent in the following detailed description taken in connection with the accompanying drawing forming a part of this specification and in which drawing:

Figure 1 is a side view of the improved clothes pin.

Figure 2 is a central longitudinal sectional view of the clothes pin.

Figure 3 is a transverse sectional view 50 taken on the line 3-3 of Figure 2.

In the drawing, where similar characters designate corresponding parts throughout the several views the letter A designates a clothes pin constructed according to our invention, and B the novel reinforcing pin.

The pin A includes a main body portion

4 as in the ordinary pin, and a head 5 formed thereon. Extending from the main body portion 4 are the two prongs 6 in spaced relation which define a slot 7 for the reception of the line or article to be gripped. The confronting faces 8 of the prongs 6 are corrugated in such a manner as to define a plurality of grooves 9 which grip the line firmly and prevent the pin from slipping off of the line. These grooves 9 extend transversely to the length of the pin so as to be in a plane parallel with the line.

Preferably at the juncture point 10 of the two prongs 6 and adjacent the main body portion 4 is inserted the reinforcing pin B.

This pin B is preferably made of a metal, or suitably treated, to withstand rust and corrosion. During the course of manufacture of the clothes pin A, the metal pin B, which may be of straight formation having its ends 11 pointed, is inserted into an aperture 12 extending thru the two prongs. These ends 11 are then bent upwardly and forced inwardly into a recess 13 and into biting contact with the main body portion 4, so that the outer edges 14 of the pin B will lie flush with the outer face of the main body portion 4 and in this manner the metal pin B is clinched into the main body portion 4 and securely protects the clothes pin from splitting. It is to be noted in the preferred embodiment of this invention that the metal pin B passes thru the two prongs 6 adjacent their juncture point, thus avoiding trans-

verse drilling of the solid portion of the clothes pin and not weakening same. It is obvious that when the two prongs 6 are placed over an article supported on the line they will spring outwardly, but due to this reinforcing pin being positioned as it is the strain will not be transmitted to the main body portion 4, thus eliminating the liability of splitting the pin and releasing of the clothes.

Changes in details may be made without departing from the spirit of the invention or the scope of the claims; but,

We claim:

1. A clothes pin comprising a main body portion having a pair of prongs extending therefrom, and a metal reinforcing pin extending thru said prongs at a point adjacent said main body portion, having its ends turned inwardly and lying flush with the outer face of the pin.

2. A clothes pin comprising a main body

portion having a pair of prongs extending therefrom, and a metal reinforcing pin extending thru said prongs having its end bent longitudinally of the main body portion and then inwardly to engage the side walls of the main body portion.

3. A clothes pin comprising a main body portion having a pair of prongs extending therefrom, and recesses at opposite sides adjacent said prongs, and a metal reinforcing pin extending thru the pin at a point intermediate the ends and at right angles to the longitudinal axis thereof, in close proximity to the juncture of said prongs, and the ends

of said reinforcing pin being bent upwardly 15 into said recesses and inwardly into biting contact with the main body portion.

4. A clothes pin comprising a main body portion having a pair of prongs extending therefrom and recesses at opposite sides adjacent said prongs, a metal reinforcing pin extending thru said prongs at a point adjacent said main body portion, and the ends of said pin being sharpened and bent upwardly into said recesses and inwardly into 20 biting contact with the main body portion. 25

LEONARD S. BALUTA.
